(57) **CLAIM**

The ornamental design for drip tray, as shown and described.

DESCRIPTION

FIGURE 1.1 is a top plan view of a first embodiment of a drip tray;

FIGURE 1.2 is a bottom plan view of the first embodiment of a drip tray;

FIGURE 1.3 is a front elevation view of the first embodiment of a drip tray;

FIGURE 1.4 is a rear elevation view of the first embodiment of a drip tray;

FIGURE 1.5 is a left side elevation view of the first embodiment of a drip tray;

FIGURE 1.6 is a right side elevation view of the first embodiment of a drip tray;

FIGURE 1.7 is a top perspective view of the first embodiment of a drip tray;

FIGURE 1.8 is a different top perspective view of the first embodiment of a drip tray;

FIGURE 1.9 is a bottom perspective view of the first embodiment of a drip tray;

FIGURE 1.10 is a different bottom perspective view of the first embodiment of a drip tray;

FIGURE 2.1 is a top plan view of a second embodiment of a drip tray;

FIGURE 2.2 is a bottom plan view of the second embodiment of a drip tray;

FIGURE 2.3 is a front elevation view of the second embodiment of a drip tray;

FIGURE 2.4 is a rear elevation view of the second embodiment of a drip tray;

FIGURE 2.5 is a left side elevation view of the second embodiment of a drip tray;

FIGURE 2.6 is a right side elevation view of the second embodiment of a drip tray;

FIGURE 2.7 is a top perspective view of the second embodiment of a drip tray;

FIGURE 2.8 is a different top perspective view of the second embodiment of a drip tray;

(Continued)

FIGURE 2.9 is a bottom perspective view of the second embodiment of a drip tray; and
 FIGURE 2.10 is a different bottom perspective view of the second embodiment of a drip tray.
